G. S. LEDDICK

ELECTRIC SWITCH

Filed July 9, 1924

Inventor:
George S. Leddick,
by Alexander S. Zent.
His Attorney.

UNITED STATES PATENT OFFICE.

GEORGE S. LEDDICK, OF SCHENECTADY, NEW YORK, ASSIGNOR TO GENERAL ELECTRIC COMPANY, A CORPORATION OF NEW YORK.

ELECTRIC SWITCH.

Application filed July 9, 1924. Serial No. 725,079.

To all whom it may concern:

Be it known that I, GEORGE S. LEDDICK, a citizen of the United States, residing at Schenectady, in the county of Schenectady, 5 State of New York, have invented certain new and useful Improvements in Electric Switches, of which the following is a specification.

My invention relates to electric switches 10 and more particularly to electric switches of the type having a plurality of movable contact fingers and a relatively movable bridging member cooperating therewith.

One of the objects of my invention is to 15 provide an improved switch of the above type in which electrical contact is established between the several contact fingers and then is broken with one of the fingers and maintained with the other fingers when 20 the movable bridging contact member is operated from one position to a second position and which is provided with means for preventing contact with the said one finger upon the return of the bridging member to 25 the first position.

Although not necessarily limited thereto my improved electric switch is especially well adapted for controlling an electromagnetic line switch of a translating device such 30 as for example an electric motor, particularly where shipper rod operation of the controlling switch is desired. In such application my improved switch takes the place of the usual stop and start push button stations and provides connections for 35 maintaining effective the under voltage protective feature of the line switch mechanism.

For a better understanding of my invention reference is had to the following description taken in connection with the accompanying drawing in which Fig. 1 is a perspective view of an electric switch embodying my invention, Fig. 2 is a perspective view showing the relative positions of 45 the several parts of the switch shown in Fig. 2 after operation to the second position, and Fig. 3 is a circuit diagram showing the connections of the switch when employed to control an electromagnetic line switch for a 50 translating device.

The novel features which I believe to be characteristic of my invention are pointed out with particularity in the appended claims.

55 Referring to Fig. 1, a switch shaft 10 is

rotatably supported in the brackets 11 and 12 which are secured to a base 13 of suitable insulating material. The central portion of shaft 10 is encased in an insulating sheath 14 upon which a bridging contact member 15 is secured by means of the clamps 16 and 17 and the screws 18. A set of contact fingers 19, 20 and 21 which are pivotally mounted in the supporting frames 22, 23 and 24 respectively are disposed in spaced alignment with the end of the contact fingers in the path of different portions of the bridging contact members 15 as shown. Each of the frames 22, 23 and 24 is notched to receive the opposing tongues 70 which extends from the sides of the contact fingers 19, 20 and 21 and the removable keys 25, 26 and 27 and the cooperating compression springs 28, 29 and 30 are provided for maintaining the several contact fingers in 75 engagement with the supporting frames and also serve to bias the contact fingers to the position shown.

An operating lever 31 is suitably secured 80 to one end of switch shaft 10 and is arranged to be connected to a shipper rod or other reciprocating operating member. A stop 32 is provided for limiting the movement of the rotatable shaft 10 when it is operated from the position shown in Fig. 1, 85 and a suitable biasing means such as the over center device shown comprising the curve member 33 and the compression spring 34 is provided for biasing the switch shaft 10 to the last position to which it is 90 operated.

It will be observed that the portion 35 of the bridging contact 15 which cooperates with the contact finger 19 is of shorter length than the portion 36 which cooperates 95 with the contact fingers 20 and 21, due to the fact that a part of the first portion has been cut away. The reverse side of contact finger 19 is covered with a sheet of suitable insulating material 37 such as hard fibre or the like which may be riveted to the contact finger as shown.

As thus constructed and arranged the operation of my improved switch mechanism is as follows: When the operating lever 31 105 is moved to the left from the position shown in Fig. 1 into the position shown in Fig. 2, the bridging contact 15 is carried into overlapping contact with all of the contact fingers 19, 20 and 21 at an intermediate pos- 110

tion, thus electrically interconnecting the same. Upon continued movement of the operating lever 31 to the left, the contact fingers 19, 20 and 21 are rotated from the position shown in Fig. 1 against the bias of the compression springs 28, 29 and 30 respectively and at a second intermediate position the shorter portion 35 of the bridging contact 15 is carried out of engagement with the end of contact finger 19 and the latter at once returns to the initial position to which it is biased by spring 28. The portion 36 of the bridging member 15 however is sufficiently long to maintain engagement with the contact fingers 20 and 21 when the operating lever 31 is operated to the extreme left hand position as shown in Fig. 2. As the switch is operated to the position shown in Fig. 2 in the manner just described, the lower end of the curved member 33 is carried over the center of switch shaft 10 and serves to bias the latter to the position to which it is operated.

Upon the return movement of the operating lever 31 from the position shown in Fig. 2, the portion 35 of the bridging member 15 engages with the insulating sheet 37 carried on the reverse side of contact finger 19 and rotates the latter to the right against the bias of spring 28. Upon reaching the first intermediate position the portion 36 of bridging contact 15 is disengaged from the fingers 20 and 21 and continued movement of the bridging contact 15 again causes the portion 35 to pass under the end of contact 19 and permits the latter to return to its biased positioned.

Thus it will be seen that electrical contact is established between the finger 19 and the portion 35 of bridging contact 15 only for a short interval during the movement of the latter from the position shown in Fig. 1 to the position shown in Fig. 2 and that electrical contact with the finger 19 is prevented upon the return movement of the contact member.

In Fig. 3, my improved switch is shown arranged to operate as a master switch for the electro-magnetic line switch 38 which controls the connection of the electric motor 39 to the supply lines 40. When the bridging contact 15 is operated from the "off" position in which it is shown to interconnect the contact fingers 19, 20 and 21 as previously described, an energizing circuit for the operating winding of switch 38 is established from the lower of the supply lines 40 through the finger 19, bridging contact 15, finger 20 and the operating winding to the middle of the supply lines 40. This causes the electromagnetic switch 38 to close and connect the motor 39 to the supply line 40. At the same time a holding circuit for the operating winding of switch 38 is established through the auxiliary contact 41 with

which the switch 38 is provided, the contact finger 21, bridging contact 15 and finger 20. Thus as the movement of bridging contact 15 is continued and contact is broken with the finger 19, the initial energizing circuit 70 for switch 38 is opened and the switch 38 is maintained energized by a circuit including the auxiliary contact 41. Hence, if the voltage of the supply line 40 decreases below the value required to maintain the switch 75 38 in the closed position the latter opens and disconnects the motor 39 from the supply line 40. Should the voltage of supply line 40 again become normal, the electromagnetic switch 38 can not be closed until the master 80 switch operating lever 31 is returned to the initial position and manually operated to complete an energizing circuit for switch 38 through the contact finger 19 as previously described.

In accordance with the provisions of the patent statutes I have described the principles of operation of my invention together with the apparatus which I now consider to represent the best embodiment thereof, but 90 I would have it understood however that the apparatus shown is only illustrative and that the invention may be carried out by other means.

What I claim as new and desire to secure by Letters Patent of the United States, is:—

1. An electric switch mechanism comprising a plurality of movable contact fingers, a relatively movable bridging member operable into overlapping contact with each of said fingers to interconnect the same, the relative length of overlapping contact with one of said fingers being less than with the other fingers whereby continued 105 operation of said member effects the disengagement of said one finger and maintains contact with said other fingers, and means for preventing electrical contact with said one finger upon the return movement of 110 said member.

2. An electric switch mechanism comprising a contact member operable between two positions, a plurality of relatively movable contact fingers each biased to a position in the path of different portions of said member and so proportioned that when the said member is operated from one position to the other electrical contact is established with all of said fingers at one intermediate position and broken with one of said fingers at a second intermediate position, and means for preventing electrical contact with said one finger upon the return of said member to the said one position. 125

3. An electric switch mechanism comprising a pivoted contact member operable between two positions, a plurality of relatively movable contact fingers each biased to a position in the path of different por- 130

tions of said member, the several portions of said member being so proportioned that when the same is operated from one position to the other electrical contact is established with all of said fingers at an intermediate position and is broken with one of said fingers at a second intermediate position, and means for preventing electrical contact with said one finger upon the 10 return of said member to said one position.

4. An electric switch mechanism comprising a pivoted contact member operable between two positions, means for biasing 15 said member to the last position to which it is operated, a plurality of pivoted contact fingers disposed in spaced relation with the ends thereof in the path of different portions of said pivoted contact member 20 and arranged to be interconnected thereby when said member is operated from one of said positions to the other, the relative lengths of one of said fingers and the co-operating portion of said contact member 25 being such that the said one finger is disengaged when said member is in the said other position, and means for preventing

electrical contact with said one finger upon the return of said member to said one position.

5. An electric switch mechanism comprising a base, a set of contact fingers pivotally mounted thereon with the ends thereof in spaced alignment, a switch shaft rotatably supported on said base, means for operating said shaft between two positions and biasing the same to the last position to which it is operated, a bridging contact member secured to said shaft and carried thereby into simultaneous overlapping electrical contact with each of said fingers when said shaft is operated from one position to an intermediate position, said bridging member having a portion cut away whereby upon continued operation of said shaft 40 to the other position one of said fingers is disengaged, and insulating means carried by said one finger for preventing electrical contact of said bridging member therewith upon the return of said shaft to 45 the said one position.

In witness whereof, I have hereunto set my hand this 8th day of July, 1924.

GEORGE S. LEDDICK.
